CLAIM

We claim the ornamental design for footwear, as shown and described.

DESCRIPTION

FIG. 1 is a perspective view of footwear, showing our new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

(Continued)

The dashed lines are included for illustrating environmental structure and form no part of the claimed design.

1 Claim, 6 Drawing Sheets
